US00D566654S

(12) **United States Design Patent** (10) **Patent No.:** **US D566,654 S**
(45) **Date of Patent:** **** Apr. 15, 2008**

(54) **ELECTRICAL ADAPTER**

(76) Inventors: **Irina Ivanova**, 164 E. 33rd St., Apt. 9, New York, NY (US) 10016; **Botir T. Sagdullaev**, 164 E. 33rd St., Apt. 9, New York, NY (US) 10016

(**) Term: **14 Years**

(21) Appl. No.: **29/250,372**

(22) Filed: **Nov. 10, 2006**

Related U.S. Application Data

(63) Continuation-in-part of application No. 29/242,439, filed on Nov. 11, 2005, now Pat. No. Des. 540,257.

(51) **LOC (8) Cl.** **13-03**

(52) **U.S. Cl.** **D13/139.7**

(57) **CLAIM**

The ornamental design for an electrical adapter, as shown and described.

DESCRIPTION

FIG. 1 is a left, front, and top perspective view of our new design for an electrical adapter;

FIG. 2 is a left side elevation view of the electrical adapter shown in FIG. 1;

FIG. 3 is a front side elevation view of the electrical adapter shown in FIG. 1;

FIG. 4 is a top plan view of the electrical adapter shown in FIG. 1;

FIG. 5 is a right side elevation view of the electrical adapter shown in FIG. 1;

FIG. 6 is rear elevation view of the electrical adapter shown in FIG. 1;

FIG. 7 is a bottom plan view of the electrical adapter shown in FIG. 1;

FIG. 8 is a left, front, and top perspective view of our new design for an electrical adapter showing an optional power input on the top side, the other sides being the same as in FIG. 1; and,

FIG. 9 is a top plan view of the electrical adapter of FIG. 8. The broken line showing of portions of the electrical adapter are included for the purpose of illustrating environmental features and forms no part of the claimed design.
